UNITED STATES PATENT OFFICE.

HARVE R. STUART, OF WHEELING, WEST VIRGINIA

TELEGRAPHONE.

No. 893,278.

Specification of Letters Patent.

Patented July 14, 1908.

Application filed September 24, 1907. Serial No. 394,294.

To all whom it may concern:

Be it known that I, HARVE R. STUART, a citizen of the United States, residing at Wheeling, in the county of Ohio and State of West Virginia, have invented certain new and useful Improvements in Telephones, of which the following is a full, clear, and exact description.

My invention relates to apparatus for magnetically recording and reproducing sound and commonly known as the telephone.

The present invention covers particularly an improvement in the circuits of the telephone apparatus by which improved results are obtained in recording and reproducing sound or any other vibrations.

In telephones, as ordinarily used, a steel disk or recording medium is continuously moved in close proximity or contact with a magnet or magnets forming part of a telephone circuit. When the recording magnet is in a transmitting telephone circuit, a magnetic record is made on the continuously moving medium, and this record is reproduced at any subsequent time when the machine is operated with the recording magnet in a receiving telephone circuit. When the machine is recording, the steel of the recording medium is magnetized under the influence of the magnetic fluctuations in the recording magnet and during the reproduction this magnet is caused to undergo the same magnetic pulsations which are converted into electric pulsations in the receiving telephone circuit. From a theoretical standpoint the action is quite complex and involves many electric and magnetic phenomena. Among such phenomena are hysteresis effects or losses in the core of the recording magnet, and particularly in the hardened steel of the recording medium. It is desirable to reduce these losses as much as possible, and my experiments have been directed to accomplishing this result.

45 In my experiments I have discovered that it is possible to attain greatly improved results by the use of a condenser connected in circuit with a battery and with the recording and reproducing magnet in a special manner.

50 It is my theory of the operation that the condenser serves to change the relation or proportion between the current pulsations in one direction and those in the other through the recording and reproducing magnet, and that this is accompanied by a correspondingly different character in the changing

magnetic conditions in the pole thereof and in the recording and reproducing medium. It appears that if the magnetic fluctuations can be caused in any way to have about equal 60 values of first north and then south polarity, that the degree of changing magnetization on the recording medium will represent the largest possible intensity variation, corresponding to the maximum efficiency of reproduction. While this is my theory of the operation, I believe that it is not quite certain just what relation to one another the various factors have in the operation. In any case, the actual practical results are 70 found to be improved by the circuits and arrangements of the present application, and if the theory above outlined is not exactly correct, there are other theoretical considerations governing the action, and at present 75 unknown to me, to which the improved result is due.

In the drawings: Figure 1 is a complete diagram showing the practical arrangement of the circuits in an actual machine; Fig. 2 80 shows diagrammatically the essential theoretical principles of the circuits when the machine is recording and when it is reproducing a record; Fig. 3 is a view similar to Fig. 2 showing the essential features of a modified 85 arrangement of the circuits in recording and reproducing relation.

Referring to the drawings, and particularly to Fig. 2 thereof, 1 indicates a transmitter, and 2 a battery in a circuit including 90 the primary 3, of an induction coil.

4 indicates the secondary of the coil which is adapted to be connected to a recording and reproducing magnet 5, by any suitable means (such as a switch later described). The circuits at this time correspond to switch position No. I in Fig. 2. When the circuits are changed for the reproducing operation the magnet 5 is connected to a telephone receiver 6, as shown at switch position No. II 95 in Fig. 2. These circuits and arrangements thus far described are of the ordinary sort in telephone apparatus.

In accordance with the present invention I provide a condenser 7, one side of which is directly connected to a battery 8, so that the condenser and the battery may be said to be in series with one another. The unconnected terminals of the condenser and the battery are put in a bridging or shunt circuit 100 about the recording or reproducing magnet 5. The result of this arrangement is to

greatly improve the strength and clearness of the record reproduction. In this action the condenser has a normal charge corresponding to the voltage of the battery so that the 5 current fluctuations of the telephone circuit which are impressed on the condenser have to be superposed on this charge. It is clear that the current pulsations of a direction tending to diminish the normal charge of the 10 condenser will be more powerful than those which tend to still further increase the potential of the condenser against the counter E. M. F. of the charge already accumulated therein. The character of the current waves 15 will therefore be changed from their normal characteristics in the condenser circuit, and this obviously produces an inverse change in the circuit of the recording and reproducing magnet 5 which is in multiple with the condenser circuit. In other words, the positive 20 and negative current values in the magnet 5 will be displaced with respect to the central or zero line of current flow. This shifting of the current waves with respect to the zero 25 line in the magnet 5 is accompanied by a corresponding change in the magnetizing action on the recording medium, with an improvement in efficiency, as already indicated.

In Fig. 3 the same apparatus and parts are 30 employed with substantially the same circuit arrangements, except that the talking battery 2 is made use of for normally charging the condenser 7 in place of the special battery 8. There is no reason why the battery 35 2 should not be made to serve this purpose since it does not interfere in any way with its regular function. This can be easily accomplished by a connection 9, from one terminal thereof, the other terminal being connected to the other side of the condenser through a wire 10, and through the secondary 40 4 of the induction coil. These connections do not disturb the regular function of the battery 2 in impressing a current 45 through the transmitter and primary 3, and the condenser will be normally charged to a voltage corresponding to the working potential of the battery. In Fig. 1 is illustrated 50 substantially the above condenser circuits are secured in an ordinary telegraphone.

Referring to Fig. 1, the transmitter 1, battery 2, the coil having primary and secondary windings 3 and 4, the recording and reproducing magnet 5, receiver 6, and condenser 7, are shown denominated in the same way as in Figs. 2 and 3. 12 indicates a switch having blades 12^a, 12^b, 12^c and 12^d. These blades are arranged and connected in such a 55 way that in the normal position of the switch the blades 12^a and 12^b are in electrical contact with one another, but in the alternate position of the switch corresponding to the recording operation of the machine the 60 blades 12^a and 12^b are separated, while 12^c,

12^c and 12^d, are all brought into electrical contact. 13 denotes a special form of telephone receiver, and known as an amplifier, and 14 indicates a magnet which traverses the same path on the recording medium as 70 the recording and reproducing magnet and which is known as the erasing magnet and serves to obliterate all previous records on the medium when in action.

The arrangement of the circuits and the 75 operation thereof are as follows: When making a record, the switch 12 is moved to the alternate position of that shown, and a circuit is completed from the battery 2, through wire l', blade 12^d, to blade 12^c, and from 80 thence to blade 12^b, wire l', wire l'', transmitter 1, wire l', primary winding 3, back to battery 2. The voice currents in this circuit under the influence of the transmitter induce currents in the secondary winding 4, which 85 traverses the following circuit: wire m', blade 12^c, blade 12^b, wire l'', magnet 5, wire m'', switch 15 wire m³, back to the secondary 4. This circuit includes secondary 4, and recording and reproducing magnet 5, as required, so that the record is properly made on the recording medium. At the same time 90 the erasing magnet 14 is constantly energized from the battery in advance of the recording and reproducing magnet by the following circuit: battery 2, wire l', blade 12^d, blade 12^c, blade 12^b, wire l'', wire n', magnet 14, wire n'', back to the battery. The condenser 7 is connected in series with the battery and bridged across the recording and reproducing magnet 5 at this time as follows: 95 Condenser 7, wire o', battery 2, wire l', blades 12^d, 12^c, wire m', winding 4, and wire o'; back to the condenser. Inasmuch as the magnet 5 is connected to the free terminal of 100 the battery at the blade 12^b, and to the free terminal of the condenser by the wire m³, at this time, it is evident that the condenser and battery are in series with one another, and together bridged or shunted across the 105 recording and reproducing magnet, as is required. The record having been made, the reproduction thereof is accomplished in substantially the usual way, and which does not constitute in itself any particular part of the 110 present invention. The switch 12 resumes its normal position shown, with blades 12^a and 12^b in contact so that a direct circuit is formed from magnet 5, through wire l'', blade 12^b, blade 12^a, receiver 6, wire p', 115 switch blade 15, wire m², back to the magnet 5. (If switch blade 15 is on the other contact shown, the other receiver or amplifier 13 will be included in this circuit in lieu of the receiver 6). In this reproducing operation 120 in accordance with the circuits of Fig. 1, the battery 2 and the condenser 7 take no part.

What I claim, is:—

1. In an apparatus for magnetically recording and reproducing sound, a magnet, 130

- a telephone circuit including said magnet, and a battery and a condenser in series with one another and bridged or shunted across said magnet.
5. In an apparatus for magnetically recording and reproducing sound, a magnet, a telephone circuit including said magnet, a battery for said telephone circuit, and a condenser joined to one terminal of said battery so as to be in a series circuit therewith bridged or shunted across said magnet.
10. In an apparatus for magnetically recording and reproducing sound, a magnet, a telephone circuit including said magnet, a condenser and a battery, and a circuit including said battery and said condenser in series with one another and bridged or shunted across said magnet.
15. In an apparatus for magnetically recording and reproducing sound, a magnet, a transmitting circuit including said magnet, and a condenser normally charged to a predetermined potential and bridged or shunted across said magnet.
20. In a telephone, a transmitting circuit including a battery, a transmitter and the primary of an induction coil, a secondary circuit including the secondary of said induction coil and a recording and reproducing magnet, and a condenser included in a shunt circuit around said magnet.
25. In a telephone, a transmitting circuit including a battery, a transmitter and the primary of an induction coil, a secondary circuit including the secondary of said induction coil and a recording and reproducing magnet, and a condenser forming part of said secondary circuit.
30. In a telephone, a primary circuit including a battery and transmitter and the
- primary of an induction coil, a secondary circuit including the secondary of said coil and a magnet, a receiver, a switch for interrupting said primary circuit and substituting said receiver for said secondary winding 45 in the secondary circuit, and a condenser adapted to form part of the secondary circuit during the recording action thereof.
35. In a telephone, a primary circuit including a battery and transmitter and the primary of an induction coil, a secondary circuit including the secondary of said coil and a magnet, a receiver, a switch for interrupting said primary circuit and substituting said receiver for said secondary winding 50 in the secondary circuit, a condenser, and means for including said condenser in a circuit in series with said battery and bridged or shunted across said magnet during the 55 recording action of the machine.
40. In a telephone, a transmitting circuit including a battery, a transmitter and the primary of an induction coil, a secondary circuit including the secondary of said coil and a magnet, a condenser permanently connected to one terminal of the battery and to a point in said secondary circuit, and a switch for closing said primary and secondary circuits and establishing a separate connection from the other battery terminal 60 to a point in said secondary circuit on the other side of said magnet and secondary winding from said condenser connection therewith.
45. In witness whereof, I subscribe my signature, in the presence of two witnesses.
